MAURICE P. SULLIVAN, OF TORRINGTON, CONNECTICUT, ASSIGNOR TO SPLITDORF ELECTRICAL COMPANY, OF NEWARK, NEW JERSEY.

SPARK-PLUG.

1,313,426.

Specification of Letters Patent.

Patented Aug. 19, 1919.

Application filed December 31, 1918. Serial No. 269,154.

To all whom it may concern:

Be it known that I, MAURICE P. SULLIVAN, a citizen of the United States, residing at Torrington, in the county of Litchfield and 5 State of Connecticut, have invented certain new and useful Improvements in Spark-Plugs, of which the following is a specification.

My invention relates to a spark plug 10 adapted for use in connection with an internal combustion engine using high tension current for ignition. Internal combustion engines of the type used in airplanes develop large power and on account of the fact that 15 the engines are running at substantially constant speed at full load for a number of hours, a great amount of heat is developed which seriously affects the spark plugs. The heat thus developed, together with the high 20 compression ordinarily used in this type of an engine, imposes severe conditions on the spark plugs, and it is the object of my present invention to provide a plug which will stand an excessive amount of heat and 25 compression at the same time one that will keep itself free from carbon so that the plug cannot be readily short circuited.

These and other objects will be apparent to one skilled in the art, after a study of 30 the annexed drawing, in which 1 is a shell threaded at the lower end 2 for screwing into the engine cylinder. The shell 1 carries an electrode 3, usually referred to as the ground electrode. The upper part of the 35 shell 1 is adapted to receive a gland 4, which, in my preferred construction, is threaded at 5 into the shell 1. A gasket 6 is used to make a gas-tight joint. It is to be understood that I may attach the gland 4 to the 40 shell 1 in any other suitable manner. The gland 4 carries a central electrode 7 which is insulated therefrom by insulating material 8, preferably of mica, which extends substantially the full length of the electrode 7. 45 The thickness of the insulating material 8 is made sufficient to withstand the potential that is applied to the electrode 7. The lower end of the electrode 7 carries an enlarged portion or head 9. In the process of manufacturing, I prefer to upset the head 9 on the electrode 7. A spark point 10 is securely fastened to the head 9 in any suitable manner. The point 10 is adapted to coöperate with the electrode 3 to form a spark gap 11. 55 Carried on the head 9 is a bushing 12. The

upper part of the bushing 12 is countersunk at 13 while the lower end 14 of the gland 4 is countersunk at 15 in a similar manner to the countersink 13. Positioned between the end 14 and the bushing 12 is an insulator 16, 60 which, in my preferred form, is of mica. This insulator extends beyond the peripheral surface of the end 14 and the bushing 12 and has its edges chamfered off to form a somewhat rounded V-shaped edge 17. The 65 upper part of the electrode 7 is threaded to receive a clamping nut 18 and a terminal nut 19. Between the gland 4 and the nut 18 is positioned an insulator 20 which can be made up of one piece of insulating material, 70 such as porcelain, or may be made up of a series of mica washers.

It will be seen from the construction described that the assembly of electrode 7 in the gland 4 is a very simple one, at the same time a very rigid one and it is also seen that the insulator 8, which insulates the electrode 7 from the gland and bushing is protected by these parts from direct contact with the burning gases in the engine cylinder, as well 75 as from oil and carbon, and I have, therefore, obtained what I term an armored plug. The object of the insulator 16 is to form a carbon breaker. I have found that an insulator, such as mica, when at or above a certain temperature, prevents deposition of carbon and I, therefore, construct the bushing 12 of metal of the right characteristics such that it will convey the proper amount of heat to the insulator 16, whose outer edge 80 I have chamfered off to provide an edge which can be raised to a temperature such as will prevent carbon from forming thereon so that I eliminate the danger of carbon forming over the edge of the insulator 16 85 to make an electrical cross between the bushing 12 and the end 14 of gland 4. I preferably provide the chamfers 13 and 15 so as to increase the leakage space between the end 14 and the bushing 12 along the surface 90 of the insulator 8. It will be noted that the surface between the parts where gas leaks may occur have been made relatively large so as to secure considerable area of contact between the parts whereby leakage may be 95 prevented.

The insulator 16 may be constructed or formed so as to have the inner portion adapted to fit the countersunk or chamfered portions 13 and 15, allowance being made for 100 105 110

suitable packing if desired. It will be further understood by those skilled in the art, that various other changes and alterations may be made in the details relating to 5 my invention, without departing from the spirit of the same and the scope of the appended claims.

Having thus described my invention, what I claim is:—

- 10 1. In a spark plug, a shell, a gland adapted to fit the upper part of said shell and having one end extending downward into the shell, a headed electrode passing through said gland and its extended end but insulated therefrom, a bushing carried by said electrode adjacent its head, a device between said bushing and said gland end for breaking up the contiguity of the surfaces thereof, and means on the outer end of the said 15 electrode for holding the parts carried by the gland securely thereto.
- 20 2. In a spark plug, a shell, a gland adapted to fit the upper part of said shell and having one end extending downward into the shell, a headed electrode passing through said gland and its extended end but insulated therefrom, a bushing carried by said electrode adjacent its head, an insulator positioned between said bushing and gland end 25 and extending beyond the peripheral surfaces of the gland and bushing toward the interior wall of the shell and means on the outer end of the electrode for holding the bushing and separating insulator securely 30 to the gland.
- 35 3. In a spark plug, a shell, a gland adapted to fit the upper part of said shell and having one end extending downward into the shell, a headed electrode passing through said gland and its extended end but insulated 40 therefrom, a bushing carried by said electrode adjacent its head, an insulator posi-

tioned between the gland end and said bushing and extending beyond their peripheral surfaces, said extended part being chamfered 45 off to form a rounded V-shaped edge and means for holding the electrode, bushing and gland securely in operative relationship.

4. In a spark plug, a shell, a gland adapted 50 to be fastened to the upper part of the shell and having a countersunk end extending downward into the shell, a central electrode carried by but insulated from the gland, a head on said electrode carrying a sparking 55 point, a bushing carried by said head and having its upper part countersunk, an insulator between the said countersunk ends of the gland and bushing and extending beyond their peripheral surface and terminating in a rounded V-shaped edge and means 60 for holding the electrode, bushing and insulator securely to the gland.

5. In a spark plug, a shell, a gland adapted 65 to be fastened to said shell, an insulator passing through said gland and extending downward into the shell, a central electrode within said insulator, a metallic armor for said extended insulator end and an insulator between said armor and said gland. 70

6. In a spark plug, a shell, a gland adapted to be fastened to said shell, an insulator passing through said gland and extending downward into the shell, a central electrode within said insulator, a metallic armor for 75 said extended insulator end and an insulator between said armor and said gland, said insulator having a rim so shaped as to be heated by said armor when the plug is in operation whereby carbon will not form 80 thereon.

In witness whereof, I affix my signature.

MAURICE P. SULLIVAN.
